UNITED STATES PATENT OFFICE.

WILLIAM ENTICOTT, OF ALLEGHENY, PENNSYLVANIA.

SHOVEL FOR LIFTING AND SIFTING ASHES.

SPECIFICATION forming part of Letters Patent No. 255,777, dated April 4, 1882.

Application filed September 10, 1881. (Model.)

To all whom it may concern:

Be it known that I, WILLIAM ENTICOTT, a citizen of the United States of America, residing at Allegheny, in the county of Allegheny and State of Pennsylvania, have invented certain new and useful Improvements in Shovels for Lifting and Sifting Ashes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to an improvement in shovels for lifting and sifting ashes; and it consists in cutting lateral slots into the bottom of the shovel, leaving between them spaces of nearly the same width as the slots, and in placing on this bottom a second movable bottom cut to coincide with the former. This movable bottom can be drawn back against a spring in the rear end of the shovel, and when in this position the intervening spaces between the slots in the movable bottom close the slots in the bottom underneath, and when by relaxing the spring the movable bottom is pushed forward the slots again coincide, thus alternately closing and opening the bottom of the shovel.

25 The accompanying drawings represent my invention.

Figure 1 is a plan view, and Fig. 2 is a vertical section of the same.

A represents the shovel; B, the handle; C, 35 the movable bottom; D, the spring, and E a wire trigger. The shovel A is of an oblong form, with sides and rear end turned up, and to the latter the handle B is attached. In the

bottom of the shovel are lateral slots, extending from side to side, separated by intervening spaces slightly wider than the slots. On this bottom of the shovel is placed a second movable one, with slots that coincide with the former. This movable bottom occupies the whole space inside the shovel, excepting only a short distance at the rear end, and here its end is turned up and pressed against by the spring D. To the turned-up rear end of the movable bottom is attached a wire trigger that passes through the spring, the rear end of the shovel, and through a staple under the handle B, where it terminates in a knob or ring. By means of this wire the movable bottom can be drawn back against the spring, and when in this position the intervening spaces between the slots in this bottom close the slots underneath, which are again opened when the spring relaxes. Thus, by alternately drawing the movable bottom back and again letting it loose, the contents of the shovel are stirred and the ashes made to fall through the slots, while the cinders remain in the shovel.

Having thus described my invention, I claim—

A shovel for lifting and sifting ashes, provided with a fixed and a movable bottom, the latter sliding on top of the former and acted upon by a spring at its rear end, substantially as described.

In testimony whereof I affix my signature in presence of two witnesses.

WILLIAM ENTICOTT.
